UNITED STATES PATENT OFFICE.

PERCY R. DRENNING, OF BALTIMORE, MARYLAND, ASSIGNOR, BY MESNE ASSIGNMENTS, TO THE SYMINGTON COMPANY, OF NEW YORK, N. Y., A CORPORATION OF MARYLAND.

DRAFT RIGGING.

Application filed January 21, 1925. Serial No. 3,844.

The invention relates to draft rigging for railway cars and particularly to cushioning or shock absorbing means interposed between the yoke and a follower mounted for movement with respect thereto and in engagement with a coupler shank.

The primary object of the invention, generally stated, is to provide a cushion device embodying standard G springs arranged in tandem.

The object of the invention, more specifically stated, is the provision of cushioning means preferably employing standard G springs in association with and mounted within an enclosing casing which is so constructed and arranged as to provide spacing means between the ends of the springs, the spacing means acting as an abutment for one spring and as an abutment for a follower engaging the other spring, the parts being of such dimensions as to be capable of installation within the cushion receiving pocket of a standard draft gear such as, for instance, a two key Farlow gear.

Another object of the invention is the provision of a cushioning device embodying standard G springs which take and cushion the initial shock, and further including supplemental springs arranged to absorb additional strain, the enclosing means for the springs acting to form an unyielding connection between the front follower and yoke in case the buffing strain reaches an excessive degree which would result, otherwise, in crushing the springs, the construction being consequently advantageous in reducing likelihood of damage to the gear.

Still another object is to provide a device of this character in which the combined spring spacing and abutment means within the casing is formed integrally therewith, it being, moreover, preferable that the abutment and spacing means be connected by an integral sleeve or bearing portion constituting a guide for a plunger carrying a follower which acts against one of the springs, the casing being, moreover, provided internally with reinforcing ribs or webs insuring strength and rigidity.

An additional object is the provision of a structure of this character which will be comparatively simple and inexpensive to manufacture and assemble, positive in its

operation, efficient in use, and durable in service.

To these and other ends, the invention comprises the various elements and combinations of elements to be hereinafter set forth.

In the drawings chosen to illustrate a preferred embodiment of the invention:

Figure 1 is a fragmentary plan view of a two key Farlow type draft gear showing my cushion device embodied or mounted therein.

Figure 2 is a longitudinal section through the cushioning device or unit alone.

Figure 3 is a cross sectional view taken on the line 3—3 of Figure 2, looking in the direction of the arrow and showing the cross sectional configuration of the spring containing pockets or compartments.

Figure 4 is a cross-sectional view taken on the line 4—4 of Figure 2, showing the provision of an integral sleeve connecting the spacing and abutment elements.

Referring to the drawings in detail, the numeral 1 designates the center sills upon the upright faces of which are mounted the cheek plates 2, and between which is located the draft rigging, here represented as being of the two key Farlow type including a horizontal yoke 3 between the arms of which is arranged the coupler shank 4 engaging against the front follower 5. Extending through the coupler shank and the follower are keys 6 and 7, and the coupler, follower, sills and cheek plates are all slotted for the accommodation of the keys, the slots in the sills and cheek plates being elongated, as is well known, to permit movement of the coupler and the follower with respect to the yoke and sills. Secured between the sills is the usual back stop 8. In gears of this type the space 9 between the rear face of the front follower 5 and the forward face of the back stop 8 constitute a pocket within which is located whatever cushioning device is employed.

In carrying out the present invention I provide a casing 10 which is preferably substantially rectangular in cross section with its longitudinal edges 11 rounded and preferably, though not necessarily, grooved or concaved, as shown. The external configuration of the casing may be the same

throughout. Formed integrally with the casing at the intermediate portion thereof is a combined spacing and abutment portion designated generally by the numeral 11 and 5 including walls or partitions 12 and 13 of similar formation connected by a plurality of radial webs 14 and 15, the former of which extend inwardly from the central portions of the top, bottom and sides of the 10 casing and the latter of which extend inwardly from the corners 11. In the present instance I have shown the walls of the partitions 12 and 13 as further connected by a cylindrical sleeve portion 16 having an opening 17 therethrough to serve as a guide for axially directing a longitudinally movable plunger 18 which is arranged within the casing. The outer portions of the casing is illustrated as formed with openings 19 between the wall or partition members 12 and 13, these openings being, for convenience, in the actual casting of this form of the casing. It is, however, to be understood that the specific plunger guide 16 is not an essential feature as it is conceivable that the 25 ribs themselves may be utilized as guides.

The provision of the combined spacing and abutment means 11 within the casing defines compartments or pockets 20 and 21 30 in the opposite end portions and these pockets are intended to receive standard G springs 22 and 23. Projecting radially inwardly from the corners of the pockets 20 and 21 are webs 24 which serve as guides for 35 the springs and which reinforce the casing. Located within the springs 22 and 23 are supplemental springs 25 of less length which function in a manner to be explained.

Located within the compartment or pocket 40 20 is a follower 26 engaged by the plunger 18 and engaging against the inner end of the spring 22 and normally in contact with the spacing and abutment wall 12. The depth of the pocket 20 and the thickness of the 45 follower 26 are such that the spring 22 is located entirely within the pocket. The pocket 21 is of less depth than the pocket 20 so that the spring 23 projects considerably therebeyond.

When the device is installed or embodied 50 within a draft gear, it may be disposed, as illustrated, within the space 9 with the forward end of the casting 10 engaging against the rear face of the front follower 5. Use is 55 made of a yoke filler 27 which is arranged within the rear end of the yoke and in engagement with the rear end of the plunger 18. With the device assembled or installed, as shown in Figure 1, it is evident that there 60 is a space 28 between the yoke filler and rear end of the casing 10. The parts are normally in the position shown in Figures 1 and 2 and under draft the yoke moves forwardly, compressing the spring 23 and moving 65 the plunger 18 and follower 26 to compress

the spring 22, the casing 10 remaining stationary against the front follower 5. After the springs 22 and 23 have been compressed to a certain extent, the supplemental springs 25 will be engaged and compressed along 70 with the other springs. Under buff, the front follower 5 moves rearwardly, forcing the casing 10 rearwardly, the plunger 18 and follower 26 thereon remaining stationary. The result is that the follower 26 will 75 compress the spring 22 between it and the rear face of the front follower 5 while the spring 23 is compressed between the yoke filler 27 and the abutment wall 13. The initial shock is thus taken by the springs 22 80 and 23 and after a certain degree of movement has occurred the supplemental springs 25 will be engaged and compressed. If the strain under buff becomes excessive so that the springs are compressed to the permissible limit, the yoke filler 27 will be engaged by the adjacent end of the casing, the casing then becoming or acting as a solid medium 85 between the follower 5 and the yoke filler for transmitting the strain directly to the back stop 8, thus preventing injury 90 to the springs and other parts.

From the foregoing it will be apparent that I have thus provided a very simple and efficient structure wherein standard G 95 springs may be utilized and arranged in tandem to constitute the shock absorbing or cushioning means in a draft gear. The casing and the combined spring spacing and abutment means therewithin are all an integral structure, the parts being so braced by means of the webs or ribs as to possess great strength and not be likely to crush in 100 the event of excessive strains.

Having now described my invention, 105 what I claim is:

1. A draft gear having springs arranged in tandem, followers at a corresponding end of each of said springs, means connecting the followers and extending axially through 110 one spring, and integral combined spacing and abutment means located between and engaging the follower of one spring and the adjacent end of the other spring and serving to direct the connecting means independently of the adjacent follower, whereby the combined length of both springs, both followers and the combined spacing and abutment means will correspond to the length of the cushion receiving pocket of a 115 standard draft gear.

2. In a draft gear including a yoke, a coupler shank and a front follower block, a cushion device comprising a casing located within the yoke and of less length than the space between said front follower block and the rear end of the yoke, said casing being formed integrally with combined spacing and abutment means defining pockets of different lengths within the outer ends of the 120 125 130

casing, springs located within said pockets, the spring within the forward pocket being contained entirely therewithin, and the spring within the rear pocket projecting 5 therebeyond, a yoke filler at the rear end of the yoke engaging against the rear end of the rear spring, a follower within the forward pocket between the rear end of the forward spring and the forward portion of 10 said combined spacing and abutment means, and a plunger slidably mounted through and longitudinally directed by said combined spacing and abutment means and axially of the rear spring with its ends engaging the 15 rear face of the forward follower and the forward face of the yoke filler.

3. In a cushioning device for a draft gear, an elongated casing formed internally with spaced wall members connected by webs and 20 constituting combined spacing and abutment means, the provision of said wall members defining pockets within the ends of the casing, springs located within said pockets, a follower located within one pocket be- 25 tween the inner end of the spring therein and the adjacent wall member, the other pocket being of less length than the spring therein whereby the spring will project therebeyond, a follower disposed against the 30 outer end of said outwardly projecting spring, and a plunger directed by and ex- tending through said wall members and dis- posed between and abutting against both followers.

35 4. In a cushioning device for a draft gear, an elongated casing formed internally with

spaced wall members connected by webs and constituting combined spacing and abutment means, the provision of said wall mem- bers defining pockets within the ends of the 40 casing, springs located within said pockets, a follower located within one pocket between the inner end of the spring therein and the adjacent wall member, the other pocket being of less length than the spring therein 45 whereby the spring will project therebeyond, a follower disposed against the outer end of said outwardly projecting spring, and a plunger disposed between and abut- 50 ting against both followers, and supplemen- tal springs located within said springs and terminating short of the outer ends thereof.

5. In a cushioning device for a draft gear, an elongated casing formed internally with spaced wall members connected by webs and 55 constituting combined spring and abutment means, said wall members defining pockets within the ends of the casing, springs located within said pockets, a follower located within one pocket between the inner 60 end of the spring therein and the adjacent wall member, the other pocket being of less length than the spring therein whereby the spring will project therebeyond, a follower disposed against the outer end of said out- 65 wardly projecting spring, and a plunger disposed between and abutting against both followers, the inner ends of said webs merg- 70 ing into a sleeve portion constituting a guide for said plunger.

In testimony whereof I affix my signature,
PERCY R. DRENNING.
